UNITED STATES PATENT OFFICE.

CHARLES H. CROSSETTE, OF CHICAGO, ILLINOIS.

NECKSCARF.

SPECIFICATION forming part of Letters Patent No. 278,316, dated May 29, 1883.

Application filed June 26, 1882. (No model.)

To all whom it may concern:

Be it known that I, CHARLES H. CROSSETTE, a citizen of the United States, residing in Chicago, county of Cook, and State of Illinois, have invented certain new and useful Improvements in Neckscarfs, of which the following is a specification.

My invention relates to improvements in neckscarfs known in the trade as "flat scarfs," 10 in which two crossed aprons and the center-piece forming the body of the scarf are stiffened by a pasteboard, termed a "shield," to give the desired curvature to and maintain the scarf in shape; and the object of my invention is to so stiffen and retain the shape of the scarf but at the same time have the center-piece flexible, so that it will adapt itself to the irregular curve formed by the overlapping free ends of the collar and lie close 15 thereto, and at the same time to permit the stiffened upper edge of the scarf likewise adapt itself to the curvature of the collar. I attain these objects by devices illustrated in the accompanying drawings, in which—

Figure 1 is a rear elevation of a scarf embodying my invention; Fig. 2, a detailed longitudinal section taken through the center of width of the shield, and Fig. 3 a front elevation of the shield detached.

Similar letters of reference indicate the same parts in the several figures of the drawings.

A represents the crossed aprons, B the center-piece, and C the neckband, of a scarf of the ordinary construction, the center-piece being suitably thickened or provided with a very flexible stiffening to keep it smooth.

Extending the width of the upper portion of and stitched to the sides of the scarf in the usual manner is a shield, D, the central and upper edge of which opposing the center-piece is recessed or cut out at E, thereby removing so much of the shield as would otherwise stiffen the center-piece having contact with the overlapping ends of a collar upon the neck of the wearer. By thus having the center-piece flexible it will be seen that when the neckband is drawn taut to hold the scarf in its operative position the center-piece will readily adapt itself to the irregular curve or bulge formed by 45 the overlapping ends of the collar and the shirt-stud, and the result is that the entire up-

per edge of the scarf will lie close to the collar and be less liable to lateral displacement than if the shield conformed to the upper edge of and extended across the center-piece, as in 55 the ordinary construction of flat scarfs.

Shields, as usually constructed and kept in stock, are sufficiently rigid to retain the scarf in shape, yet flexible enough to permit the scarf to be given the desired curvature to conform to the neck and breast of the wearer. Hence it will be understood that the ordinary shield may be made to conform to my invention by simply recessing or cutting out a portion of the upper edge sufficient to conform to 60 its requirements.

If desirable to have the scarf shaped while in stock, to give it a particular and permanent curvature, or to re-enforce the shield, a metal strip, F, (shown in dotted lines in Fig. 1,) may 65 be secured to and extend across the under side of the shield; but this strip is not an absolute necessity, though sometimes preferable. For the purpose of aiding in retaining the scarf in its operative position, a loop, G, of 70 rubber cord is secured to the shield by means of an eyelet or other suitable means, which is intended to be slipped over the shirt-stud, the position of the loop being such that it will suspend the scarf while the neckband is being 75 inserted and caught upon the needle to retain it in position.

Having thus described my invention, what I claim, and desire to secure by Letters Patent, is—

1. The combination, with a flat scarf having a flexible center-piece and a neckband rigidly secured at one end to the body of the scarf, and at the other end removably secured to a needle, of a continuous shield provided 80 with a recess in its upper edge opposing the center-piece, and of a metal strip re-enforcing said shield, substantially as described.

2. The combination, with a flat scarf having a flexible center-piece, a neckband, and needle, of a shield, D, provided with a recess, E, and with a flexible loop, G, substantially as described.

CHARLES H. CROSSETTE.
